UNITED STATES PATENT OFFICE.

FREDERICK MERIAM WHEELER, OF MONTCLAIR, NEW JERSEY, ASSIGNOR
TO THE WHEELER CONDENSER AND ENGINEERING COMPANY, OF NEW
YORK, N. Y.

COMBINED FEED-WATER HEATER AND AUXILIARY CONDENSER.

SPECIFICATION forming part of Letters Patent No. 651,152, dated June 5, 1900.

Application filed December 1, 1899. Serial No. 738,814. (No model.)

To all whom it may concern:

Be it known that I, FREDERICK MERIAM WHEELER, a citizen of the United States, residing at Montclair, in the county of Essex and State of New Jersey, have invented an Improvement in a Combined Feed-Water Heater and Auxiliary Condenser, of which the following is a specification.

In steam vessels there are usually steam-
engines for performing various operations
aboard the vessel, and these engines are re-
quired both while the vessel is in port and
also while at sea; but of course when a steam-
ship is at anchor or discharging or receiving
cargo in port the main engines are not made
use of. It is important to provide at all
times for heating the feed-water and also for
condensing the steam, whether the same
passes from the main engine or from auxil-
iary engines.

The object of the present invention is to
employ one device as a condenser for the
steam from auxiliary engines when the vessel
is in port and to use the same apparatus as
the feed-water heater for the feed-supply to
the main boilers, the feed-water acting as the
condensing medium for the steam from the
auxiliary engines.

In the drawing I have represented by a ver-
tical section and elevation the present im-
provement in connection with a vertical com-
bined feed-water heater and auxiliary con-
denser; but any suitable character of con-
denser may be made use of. I have, how-
ever, represented a series of tubes I, through
which the condensing-water passes, and there
is the cock A' in the pipe C, extending from the
condenser to the circulating-pump D, and
the cock B' is in the pipe E, that passes away
from the vessel for the discharge of salt wa-
ter into the sea. The hot-well F is below the
condenser A, and into this a pipe F' leads
from the condenser of the main engines, and
there is a feed-pump G, connected by the
pipe 4 to the hot-well, and the pipe 5 from
this pump G leads to the pipe 6, that conveys
the feed-water to the boiler, and there is a
cock 18 in the pipe 6. There is also a branch
7 and cock 8 to the water-supply chamber
9 of the condenser and another pipe 10 there-

from to the boiler, with a cock 11 adjacent
to the cock B' in the pipe E. Under the ordi-
nary circumstances of use when in port the
circulating-pump D draws the salt water
through the pipe D' and passes the same 55
through the pipe C and cock A' and through
the tubes I in the condenser and away through
the cock B' and by the discharge-pipe E.
The steam from the auxiliary engines and
pumps that may be working in the vessel al-
ways comes in by the pipe H into the con-
denser A, and by the action of the tubes I,
which are always cooler than the incoming
steam, such steam is condensed and falls into
the hot-well F, and into the same hot-well 65
may pass the water from the condenser of
the main engines, and the feed-pump G is
adapted to take all the water that comes
into the hot-well and force it through the
pipe 5, and if now the cock 18 is opened and 70
the cocks 8 and 11 closed the water will pass
directly to the boiler by the pipes 5 and 6 and
cock 18. If the vessel is at sea, the cock A'
will be closed and the circulating-pump D
stopped and the cock B' also closed, and if the 75
cock 18 is now closed and the cocks 8 and 11
are opened the feed-water as forced through
the pipe 5 by the feed-pump G from the hot-
well goes through the pipe 7, cock 8, and
through the tubes I in the condenser, (through 80
which the salt water ordinarily passes from
the circulating-pump D,) and then this feed-
water passes by the pipe 10 and cock 11 to the
boiler, and as this feed-water passes through
the tubes I of the condenser it becomes heated 85
in its temperature in consequence of the heat
from the steam that comes into the condenser
from the exhausts of the main engines and
any auxiliary engines, pumps, &c., that may
be in operation performing duties on ship- 90
board while the vessel is at sea. By this means
the one condensing device serves as a con-
denser under all circumstances. It is availa-
ble as a feed-water heater for obtaining addi-
tional heat to the feed-water when the vessel 95
is under way and the main engines are in use.
When the vessel is at anchor and the auxil-
iary engines and pumps are in use, the circu-
lating-pump D is brought into operation to
cause the salt water to pass through the tubes 100

I and effect the condensation of all the steam coming from said devices. The water of condensation from the hot-well in this instance goes directly to the boiler by the pipe 6 in-
5 stead of going indirectly by the pipes 7 and 10 when the circulating-pump is out of action.

The relations and relative positions of the pipes may be varied according to the character of the condenser and the other features 10 of the steam arrangements in the vessel. In all instances, however, the water from the main condenser passes into the hot-well, and the steam from all auxiliary engines passes into the condenser, and the condenser is kept 15 at the proper temperature either by the external water passed through the circulating-pump and through the condenser or by the feed-water being directed through the condenser when the external water is excluded.

20 I claim as my invention—

1. The combination in a condenser with a circulating-pump and a feed-pump, of means for passing external cooling-water through and away from the condenser for condensing 25 the steam and means for returning the water of condensation to the boiler, and means for closing off the circulating-pump and external cooling-water and a pipe and cock connecting with the inlet to the condenser and a 30 pipe and cock connecting with the outlet from

the condenser, for passing the feed-water through the condenser on its way to the boiler for condensing the steam therein, substantially as specified.

2. The combination with the condenser and 35 the circulating pump and pipes for directing external water through the condenser and a hot-well and feed-pump, of pipes leading from the feed-pump the one to the boiler and the other to the circulating-pipe for the external 40 water, and cocks in said pipes, a cock for shutting off such external circulating water, a pipe for taking away the circulating water and a cock for closing the same, and a pipe leading to the boiler from the discharge side of the 45 circulating-pipe of the condenser and a cock for closing the same, whereby the feed-water can be directed through the condenser for cooling the same and for condensing the steam passing into such condenser when the external 50 circulating water is shut off from such condenser and the circulating-pump stopped, substantially as set forth.

Signed by me this 23d day of November, 1899.

FREDK. MERIAM WHEELER.
